UNITED STATES PATENT OFFICE

CHRISTINE SMITH, OF DES MOINES, IOWA

DESIGN FOR A DOLL

Application filed May 14, 1931. Serial No. 39,852. Term of patent 3½ years.

To all whom it may concern:

Be it known that I, CHRISTINE SMITH, a citizen of the United States, residing at Des Moines, in the county of Polk and State of Iowa, have invented a new, original, and ornamental Design for Dolls, of which the following is a specification, reference being had to the accompanying drawings, forming part thereof.

Fig. 1 is a front view, Fig. 2 is a back view of my doll and Fig. 3 is a side view of the upper portion of my doll, showing my new design.

I claim:

The ornamental design for a doll, as shown.

CHRISTINE SMITH.
